DESIGN FOR A GAME BOARD

Earl J. Reiff, Alliance, Ohio

Application July 17, 1945, Serial No. 120,766

Term of patent 3½ years

(Cl. D34—5)

To all whom it may concern:

Be it known that I, Earl J. Reiff, a citizen of the United States, residing at Alliance, in the county of Stark and State of Ohio, have invented a new, original, and ornamental Design for a Game Board, of which the following is a specification, reference being had to the accompanying drawing, forming part thereof.

The figure is a plan view of a game board showing my new design.

The game board is of conventional thickness.

I claim:

The ornamental design for a game board, substantially as shown and described.

EARL J. REIFF.
